LIGHT PROJECTOR

Eugène Tabouret, Argentan, France

Application July 23, 1956, Serial No. 599,545

Claims priority, application France July 27, 1955

5 Claims. (Cl. 240—1.1)

This invention relates to electric lighting apparatus and more particularly to a lighting apparatus adapted for use as a headlamp for any vehicle or as a projector in many different applications. This lighting apparatus is designed to have non-dazzle properties while having the same illuminating power as any conventional lighting apparatus. Another feature of this apparatus is that it will not alter the colors of the objects illuminated thereby.

This lighting apparatus comprises essentially a light source, for example an electric lamp, and a reflector. It encloses, in front of the lamp, a network of parallel colored blades having different colors corresponding to the main colors of the solar spectrum, with at least three colors, preferably those generally used in the trichromatic or three-color process, that is, blue, green and red.

Thus, the light rays emitted from the lamp and reflected by the reflector are colored either as they pass through the colored blades, or by their reflection on these blades. Consequently, these light rays take the colors of the main simple light elements of the decomposition spectrum of composite light. Then, by virtue of the aforesaid reflections on the blades and reflector, these light rays combine together to form another composite, non-dazzle light.

The lighting apparatus according to the invention encloses in addition a vertical screen consisting of transparent tubes disposed side by side in front of the aforesaid network of colored blades and at right angles to the axis of the apparatus. The light rays colored by the blades are thus intimately combined together due to the deflection of the light rays as they pass through the row of tubes.

According to an advantageous embodiment of this invention, the blades are carried by the front glass of the lighting apparatus or the screen of vertical transparent tubes. These blades and the glass or screen constitute a unitary structure adapted to be mounted within a headlamp of existing type for quickly and easily converting same into an improved headlamp according to this invention.

Other features and advantages of the invention, as well as various possible and alternate embodiments thereof, will be described hereafter with reference to the accompanying drawings forming part of this specification and illustrating diagrammatically by way of example the manner in which the same may be carried out in the practice.

In the drawings:

Figure 1 is a horizontal section showing an embodiment of a headlamp, with the colored blades as seen from beneath;

Figure 2 is a similar view showing in horizontal section a modified embodiment of the headlamp of Fig. 1;

Figure 3 is a similar view showing also in horizontal section another embodiment of the same headlamp;

Figures 4 and 5 are vertical sections of other embodiments.

2

The lighting apparatus illustrated in the drawings is a headlamp comprising a conventional parabolic reflector 1 and an incandescent lamp 2. In this headlamp are disposed in front of the lamp 2 a series of flat blades 3, 4, 5, 6, 7, 8 and 9 parallel to the axis of the apparatus. The number of blades used in the apparatus is immaterial; however, an odd number of blades is preferred so that a middle blade will be positioned in axial alignment with the lamp 2.

According to the primary feature of this invention the blades 3, 4 . . . 9 are colored, there being at least three different colors, preferably those employed in the trichromatic process: blue, green and red. Thus, the middle blade 6 may be blue, with green blades 3, 4, 5 on the left-hand side and red blades 7, 8, 9 on the right-hand side. Of course, the color arrangement may be reversed, that is, by disposing the green blades on the right and the red blades on the left.

Furthermore and still within the scope of this invention the outermost blades, that is the lateral blades 3 and 9, may be yellow, the blades 4, 5 alone being green and the blades 7, 8 alone being red. With the same number of blades it is also possible to have the left-hand blades 4, 3 light green and yellow, respectively, the blade 5 alone remaining green and the right-hand blades 8, 9 being orange and yellow respectively, the blade 7 remaining red. In this case, the middle blade 6 will remain blue.

As already stated hereinabove, the number of blades is immaterial, and may even be reduced to that of the different colors used.

In all cases, the composite light rays emitted from the light source and reflected by the reflector are colored as they pass through or are reflected by the colored blades. More particularly, they are colored in the various colors corresponding to the blade colors and therefore in the colors of the main elementary colors of the decomposition spectrum of composite light. Then, due to the different reflections on these blades and also on the reflector, these colored rays of simple lights combine together and form a beam of composite light. However, this double operation will produce a beam of composite light which is non-dazzling. Moreover, this light beam provides a high degree of visibility, even in foggy weather.

Consequently, the use of this headlamp is particularly effective on automotive vehicles and other vehicles to provide an improved road illumination ahead of the vehicle and avoid any risk of dazzling the drivers of on-coming vehicles. However, it will be readily understood that the use of this headlamp or projector is not restricted to this specific application, more especially as the light emitted by this improved apparatus does not alter the colors of the objects illuminated thereby. In fact, this improved apparatus may be used as a fixed lighting apparatus whenever a non-dazzle illumination is to be obtained in a given direction. Thus, it can be used in public or street lighting systems, or as an airfield beacon, or as a lighting apparatus for show-windows, operating theatres, film studios, etc.

Preferably, the color of each blade is of decreasing strength or depth in the downward direction, and if desired the lower end of the blade may be colorless. Thus, the light emitted by the headlamp or projector is damped considerably in the upward direction since the blade color is darkest in the upper region.

The parallel blades may consist of transparent or translucent material tinted bodily by means of a coloring substance or any other coloring covering. Suitably tinted mirrors may also be used to this end. If need be completely opaque glass or other plates may be used.

These blades are of decreasing width, the middle blade

6 being wider and the outermost blades 3 and 9 narrower and shorter.

To dim the light in the upper portion of the apparatus, the rear edges of the parallel blades, instead of being straight and vertical, may be shaped to conform the contour of the lamp bulb 2 in their upper portions, so as to somewhat wrap it, as shown in Fig. 4.

On the other hand, the lighting apparatus according to the invention includes, in combination with colored blades, a transverse screen consisting of a set of transparent vertical tubes 29 disposed side by side. Due to the deviations imposed by these tubes to the light rays colored by the colored blades, the transparent tubes will provide an intimate combination of these colored rays to produce another composite light having non-dazzle properties and which will not alter the colors of the objects illuminated thereby. On the other hand, these tubes will provide a perfect diffusion of the composite light issuing from the headlamp. Thus, these tubes have an important function in combination with the colored blades.

The front edges of the colored blades may be interposed between adjacent tubes 29 and form an integral unit with the screen consisting of this set of tubes, so as to constitute a device adapted to be mounted within a headlamp of conventional design for converting it into an improved apparatus according to this invention. The front glass may be fluted as indicated at 30 in Fig. 1 or plain as indicated at 10 in Figs. 2 and 3.

Figure 2 shows a modified embodiment of the tube assembly provided with parallel vertical blades. This assembly comprises a double row of tubes, the rear row 29 carrying as in the preceding embodiment the vertical plates 28 and supporting at the front the other row of tubes 29a, the tubes of this other row being off-set relative to those of the rear row so as to have their axes co-planar with the parallel blades 4, 5, 6, 7, 8.

The tubes 29 of the embodiment shown in Fig. 1, or those 29, 29a of the modified embodiment of Fig. 2 may be transparent or translucent, or ground (frosted), or silvered, or even tinted in different colors, as desired. These tubes may be made of glass, plastic or any other suitable material, and their cross-sectional contours may have different forms, such as oval, round, square, rectangular, etc. The cross-sectional area of these tubes is more or less important.

If desired, the tubes 29 and 29a may be replaced by solid rods of glass, plastic or any other suitable material.

Figure 3 illustrates another embodiment of this invention, wherein the width of the parallel blades is considerably reduced, these blades being located within the transparent tubes 29 themselves. All these tubes are parallel to one another and form an integral unit constituting a network in the form of a vertical screen in front of the lamp 2. Of course, the parallel and narrower blades 31 are colored as in the preceding embodiments described hereinabove.

Another possible form of embodiment of the invention is illustrated in Figs. 4 to 5 and comprises normal colored blades associated with vertical tubes, but in this case the tubes are filled with transparent balls 35 forming vertical rows therein, as shown. Colored or colorless balls may be used. If desired, balls 35a and 35b of different diameters may be used, as shown in Figure 5.

To convert a conventional or existing headlamp into an improved headlamp according to this invention it is also possible to either replace its front glass by a glass 10 carrying parallel colored blades, or fit therein an intermediate transparent or translucent screen provided with these blades, or mount a screen consisting of vertical tubes carrying these blades.

What I claim as new is:

1. Lighting apparatus comprising a light source, a concave reflector disposed behind and coaxially to said light source, a series of blades parallel to one another and to the reflector axis which are disposed in advance of the light source and colored with different colors comprising at least the three fundamental colors of the solar spectrum, the relative positions of said light source and said parallel blades, in relation to said reflector, being such that the light rays reflected by said reflector strike at least one portion of said blades whereby said rays are colored with the fundamental colors of the spectrum, a screen disposed in advance of said network of colored blades, at right angles to the axis of said reflector, which consists of transparent tubes disposed side by side, said screen being adapted to mix said colored rays and to emit on the side opposite to said light source a uniformly diffused white, non-glare light, through an angle of 180°.

2. Lighting apparatus according to claim 1, and including transparent balls stacked on one another in the transparent tubes so as to form vertical rows of superposed balls therein.

3. Lighting apparatus as set forth in claim 1, wherein said screen comprises another row of tubes similar to said transparent tubes and staggered relative thereto, in front of the first row.

4. Lighting apparatus comprising a light source, a concave reflector disposed behind and coaxially with said light source, a vertical screen at right angles to the axis of the assembly and consisting of transparent tubes disposed side by side, a network of parallel colored blades disposed in front of the light source and having at least three different colors of the solar spectrum, each of said blades having a reduced width and being disposed within one of said transparent tubes of said vertical screen.

5. A lighting apparatus comprising, in combination, a light source; a concave reflector having an axis passing substantially through the center of the light source and being arranged on one side of said light source; a plurality of blades arranged spaced from and parallel to each other and to the reflector axis at the other side of the light source, said blades being respectively colored with different colors comprising at least the three fundamental colors of the solar spectrum, so that the light rays reflected by said reflector strike at least a portion of each blade whereby said rays are colored with the fundamental colors of the spectrum; and means for mixing the thus colored light rays and comprising at least one row of elongated transparent elements arranged side by side at right angles to the reflector axis forwardly of said blades so that the colored rays will pass through said elongated transparent elements, whereby a diffused, white, anti-glare light will be emitted from the lighting apparatus.
